SUPPORT FOR TELEPHONE RECEIVING AND TRANSMITTING SETS

Filed Jan. 25, 1926

UNITED STATES PATENT OFFICE

WILLIAM M. VALENTINE, OF ROCHESTER, NEW YORK

SUPPORT FOR TELEPHONE RECEIVING AND TRANSMITTING SETS

Application filed January 25, 1926. Serial No. 83,426.

The present invention relates to supports for telephone receiving and transmitting sets and an object of the invention is to provide a support which will enable the set to be readily removed from the support and, at the same time, will hold the set against accidental displacement by the support. A further object of the invention is to provide a support which will be inexpensive to manufacture, simple in construction and will effectively hold a telephone receiving set against accidental displacement therefrom.

To these and other ends, the invention consists of certain parts and combinations of parts, all of which will be hereinafter described: the novel features being pointed out in the appended claims.

In the drawings:

- Fig. 1 is a plan view of the support;
 20 Fig. 2 is a section on the line 2—2, Fig. 1;
 Fig. 3 is a perspective view of the support showing the base of a telephone receiving set; and

Fig. 4 is a detail view of the stop used on 25 the conductors.

It is well-known that telephone receiving sets are in many instances injured by being displaced accidentally from their support. Provision has heretofore been made for holding the set to the support, but this holding means has been such that the removal of the set from the support has been accomplished only with difficulty and as a consequence the user of the telephone set has been unable to 30 immediately remove the set from the support for the purpose of holding the set in his or her hands.

According to this invention the set is so connected to the support that accidental blows on the side will not displace the same from the support nor will pull on the conductor wires cause such displacement.

An embodiment of this invention comprises a base member 1 having any suitable attaching means such as ears 2 depending from the base member at the rear edge thereof and adapted to be secured by screw fasteners 3 to any suitable supporting means 4. The base member preferably has a flat top and may be formed with marginal ribs 5 arranged to co-

operate with the base piece 6 of the telephone set. One of the main features of this invention is the provision of a slot or recess 7 which extends from one edge, in this instance the front edge of the support, inwardly beyond the opposite edge of the base 6 of a receiving set support on the base piece 1. This slot or way preferably has a sharp bend 8 therein adjacent the inner end thereof. In order to strengthen the base especially when the latter is made of casting, ribs 7^a may be formed on the underside of the base on the opposite sides of the slot. The slot is provided in order that the conductors 9 of the telephone set may be passed inwardly from the outer end toward the rear end of the slot beyond the bend 8. In this way when the base of the telephone set rests upon the base piece 1, the conductors which connect with the base piece 6 pass downwardly through the base. As a consequence should any accidental pulls be imparted to the conductors, the tendency would be to draw the base member 6 of the set more firmly to the base piece 1 of the support and hold the set more firmly to the support.

In order to prevent accidental blows on the top of the receiving set displacing the set from the support, a stop may be arranged on the conductors 9. In this instance, this stop comprises two plates 10 fastened together by screws 11 and adapted to be clamped upon the conductors below the support. This stop is larger than the width of the slot 7 and as a consequence should a blow be given to the telephone set tending to displace the latter from the support, the stop will cooperate with the underside of the support on opposite sides of the slot 7 and hold the set to the support. The bend 8 is provided in order to prevent the conductor wires moving freely toward the outer end of the slot. The lugs 5 at the margin of the support 1 serve to engage the base 6 on the support and prevent accidental lateral displacement of the set, particularly in connection with the stop on the conductor wires.

It will be seen that the receiving set may be readily disconnected from the support by lifting the base 6 to clear the lips or projections 5 and then drawing the conductor

wires with the stop thereon forwardly through the slots 7 to the outer end thereof. The set may be readily placed on the support by reversing this action.

5 What I claim as my invention and desire to secure by Letters Patent is:

1. A support for a telephone set comprising a supporting base having a supporting surface on which the base of the telephone set may rest, said supporting base having a slot extending from the forward edge thereof rearwardly through the supporting surface to a point in rear of that portion of the surface designed to be engaged by the base of the telephone set through which the cord of the telephone set may lead from the base, said slot having a bend adjacent the inner end thereof for retarding the movement of the cord.
- 10 2. In combination with a member to be supported provided with a cord, a supporting base having a slot opening in one end at the forward edge of the support through which the cord passes, and a stop secured to the cord below the base to cooperate with the underside of the latter in order to hold the member to the support, said stop being movable with the cord in order to permit such cord to be passed through the open end of the slot.
- 15 3. A support for telephone sets comprising attaching means, a base projecting forwardly from the attaching means and having a wide supporting surface for the base of a standard telephone set, said supporting base having a slot open at the front edge of the base at the side opposite the supporting means and extending rearwardly toward the attaching means to a point in rear of that portion of the base designed to be engaged by the base of the telephone set.
- 20 4. A support for telephone sets comprising attaching means, a base projecting forwardly from the attaching means and having a wide supporting surface for the base of a standard telephone set, said supporting base having a slot open at the front edge of the base at the side opposite the supporting means and extending rearwardly toward the attaching means to a point in rear of that portion of the base designed to be engaged by the base of the telephone set and having an offset portion adjacent its rear end.

WILLIAM M. VALENTINE.
